UNITED STATES PATENT OFFICE.

HENRY R. RICHARDSON, OF ST. LOUIS, MISSOURI.

REGISTER.

SPECIFICATION forming part of Letters Patent No. 714,745, dated December 2, 1902.

Application filed October 12, 1901. Serial No. 78,429. (No model.)

To all whom it may concern:

Be it known that I, HENRY R. RICHARDSON, of St. Louis, Missouri, have invented certain new and useful Improvements in Travelers' Expense-Registers, of which the following is a specification.

My invention relates to cash-registers, particularly to that class known as "calculators" or "adding-registers," and is designed as an improvement over the device shown and described in Letters Patent of the United States No. 668,859, granted to me February 26, 1901.

The object of my invention is to provide a pocket-register whereby the traveler can ascertain at a glance the totals of the separate expense accounts and the aggregate totals of all the accounts.

A further object of the invention is to simplify the construction of the register described in the above-named Letters Patent to the end that the same may be more economical to manufacture and easier to operate.

Other objects of the invention will appear from the following detailed description.

The invention consists generally in providing a series of item hands and dials, an operating mechanism therefor, the grand-total dial and indicator hands, and operative connections between said item-hands and said grand-total hands whereby movement of the former will be registered by the latter.

Further, the invention consists in improved means for operating said item-hands.

Further, the invention consists in means whereby the grand-total hands may be moved forward independent of the item-hands; and, further, the invention consists in various constructions and combinations, all as hereininafter described, and particularly pointed out in the claims.

In the accompanying drawings, forming part of this specification, Figure 1 is a front view of a register embodying my invention.

Fig. 2 is a sectional view on the line *j j* of Fig.

Fig. 3 is a sectional view on the line *H H* of Fig. 6. Fig. 4 is a sectional view on the line *f f* of Fig. 6. Fig. 5 is a sectional view on the line *g g* of Fig. 6. Fig. 6 is a sectional view on the line *e e* of Fig. 2. Fig. 7 is a sectional view on the line *c c* of Fig. 2. Fig. 8 is a sectional view on the line *d d* of Fig. 4. Fig. 9 is a sectional view on the line *b b* of

Fig. 2. Fig. 10 is a sectional view on the line *a a* of Fig. 3. Fig. 11 is a sectional view on the line *k k* of Fig. 6.

The operating mechanism of this device is the same on both sides of the division-line *jj* of Fig. 6, that of one side being merely a multiplication or duplication of the other to provide a series of independent registers for the different expense accounts. The mechanism being the same, I will not attempt to describe both sides of the register in detail, it being sufficient to explain the construction and operation of the upper and lower dial parts on one side, indicating the corresponding parts on the other side by the same reference-figures.

In the drawings, 2 represents the case, that is preferably of the form and size of a watch-case, wherein the operating mechanism of the register is arranged between plates 3 and 4, that are secured together at intervals by posts 5. The case is provided with the usual pendant 6, having a ring 7 and a stem 8, provided with a finger-grip or knob 9. This stem is connected with the grand-total-indicator hands by a mechanism to be hereinafter described. Near the pendant, projecting through a hole in the casing, is a stem 10, provided with a knob 11 and with an annular groove 12, that is engaged by a screw 13 and prevents the withdrawal of the stem from the case, while permitting its rotation therein. The stem has a squared end 14 to enter a correspondingly-shaped socket in a collar 15, that is secured on the squared end of a spindle 16. A corresponding collar 15^a is provided on the opposite squared end of said spindle, and said collars are adapted to turn in bearings in the lugs 17, that are secured to the front plate 3. Slidably arranged on the squared ends of said spindle are clutches 18 and 18^a, that are normally held forward by springs 19 in engagement with the toothed hubs of miter-gears 20 and 20^a, that are provided on the central rounded portion of said spindle and adapted to turn freely thereon. Between said miter-gears a stud 21 is provided, mounted in the plate 4 and provided with a sleeve 22, secured thereon and carrying a miter-gear 23, whose teeth are adapted to register with the gear 20^a. Mounted on the sleeve 22 is a second gear 24, whose teeth engage those of the gear 20 and provided with a hub 25. The sleeve 22 turns

freely on its supporting-stud, and the hub 25 and its gear turn on said sleeve 22, so that one gear and its connections may be operated independently of the other gear and its connections. Upon the sleeve 22 I provide a gear 26, having a ratchet 27 secured to said gear, both being fastened on said sleeve, and on the hub 25 I secure a gear 26^a, having a ratchet 27^a. Between the ratchets 27 and 27^a on said hub 25 is loosely mounted a gear 28, having on one side a dog 29 to engage the teeth of the ratchet 27 and on its opposite side a corresponding dog 29^a to engage the teeth of the ratchet 27^a. These dogs are held in engagement with their ratchets by suitable springs 30. Rotation of the spindle in one direction will through one of the ratchets revolve the gear 28, while the opposite ratchet will be inoperative and rotation of the spindle in the opposite direction will reverse the operation of the ratchets.

Above and below the miter-gear mechanism I provide arbors 31 and 31^a, mounted in the plates 3 and 4 and carrying the long or item hands 32 and 32^a. Upon these arbors are secured sleeves 33 and 33^a, whereon gears 34 and 34^a are secured and also ratchets 35, which are engaged by spring-pawl 36 on the plate 4 and whereby backward movement of the arbors and hands is prevented. I also provide pinions 37 and 37^a on the sleeves 33 and 33^a, to which the gears 34 and 34^a are firmly secured. The gear 26^a meshes with the gear 34^a on the upper long-hand arbor, and the gear 26 meshes with the gear 34 on the lower long-hand arbor. As the clutches on the spindle 16 are alternately operative, according to the direction in which the spindle is turned, it follows that when the spindle is rotated in one direction one of the long-hand arbors will be revolved and when the spindle is rotated in the other direction the other long-hand arbor will be revolved. In the construction that I have shown herein movement of the spindle to the right operates the hands on the lower item-dial and the reverse movement the upper hands. One spindle therefore controls the movement of the hands on both dials.

Loosely mounted on the arbors 31 and 31^a are sleeves 38 and 38^a, forming the short-hand arbors, whereon gears 40 and 40^a are secured. These sleeves 38 and 38^a project through the plate 3 and carry the short or total hands 41 and 41^a of the item-dials. I prefer to provide four of these item-dials (indicated by references 42 and 42^a) upon each side of the division-line *jj*, each dial being appropriated for a single expense and all the items that are chargeable to that expense being registered on its particular dial. The item-dials may be suitably graduated, and I prefer to provide two circles of graduations for each dial, one within the other, the inner appropriated for the short hand and the other for the long hand. The outer circle of graduations is preferably marked in multiples of five

from five cents to one hundred and the inner circle from one to twenty-five, representing a corresponding number of dollars. The short hands of the item-dials register the totals of the long hands, and as the totals of the graduations of the inner circle are twenty-five times as much as those of the outer circles and as the long and short indicator-hands move together it is necessary to gear down the short hands, so that their speed with reference to the long hands will be in the ratio of twenty-five to one—that is, the long hands and their arbors will make twenty-five revolutions of the dial while the short hands are making one. To this end I provide studs 43, secured in the plates 3 and 4, and whereon a series of idle gears are loosely mounted. These gears 44 and 44^a are located above and below the center of the case along the middle line of the same and mesh, respectively, with the pinions 37 and 37^a and carry pinions 45 and 45^a, that in turn mesh with the gears 40 and 40^a on the short-hand arbors 38 and 38^a. These gears and their pinions are provided with the requisite number of teeth to cause one revolution of the short-hand arbors to twenty-five of the long-hand arbors. The two idle gears 44 and 44^a below the center of the casing mesh, respectively, with the gears of the lower item-dials, while the idle gears above the center mesh with the gears of the upper item-dials. The loose gear 28 meshes with a gear 46, mounted on a sleeve 47, that is secured on the arbor 48, whereon the long hand 49 of the grand-total dial 50 is mounted. The gear 28 is loose on its support and is driven forward only as one or the other of the ratchets 27 and 27^a is operated by the movement of the gears 26 and 26^a. The gear 28 being connected with the gears of both the upper and lower item-dials will be revolved when either one of them is operated, and consequently movement of either the gear 26 or 26^a will be communicated to the long hand 49 of the center dial. This dial is graduated to represent dollars from one to one hundred and is also adapted to indicate cents from one to one hundred for the long hand 49. Movement of the long hands of any one or all of the item-dials will be instantly communicated through the gearings heretofore described to the long hand of the center dial, which will be moved to indicate the total of the cents registered by the long hands of said item-dials.

On the arbor 48 I provide a sleeve 51 for the short hand 52 of the grand-total or center dial. This hand 52 moves over the same graduations as the hand 49, but is geared with respect to said hand in the ratio of one hundred to one—that is, the long hand 49 makes one hundred revolutions of the dial while the short hand is making one. This relative movement of the grand-total hands I prefer to accomplish in the following manner: A pinion 53 is secured on the sleeve 47, meshing with a gear 54, loosely mounted on the

stud 43 and provided with a pinion 55, that engages a gear 56, secured to a pinion 57, loosely mounted on the arbor 51 and meshing with a gear 58 on the upper arbor 43 and carrying a pinion 59, that meshes with a gear 60, secured on the arbor 51. These gears and pinions are provided with the requisite number of teeth to cause the speed of the arbors 48 and 51 and the hands carried thereby to be in the ratio of one hundred to one. The gear 58 has beveled teeth on one side meshing with the teeth of a beveled pinion 61, arranged between friction-blocks 62 and 63, the latter being yieldingly adjustable with respect to the former by means of set-screws 64 and springs 65. The pinion 61 has an annular groove 66, adapted to receive a screw 67, which permits the pinion to turn freely, but prevents its longitudinal movement. The pinion 61 at its upper end is provided with a squared socket to receive the correspondingly-shaped end of the main stem 8. By means of this connection the grand - total hands can be moved forward independently of the hands of the item-dials.

In using my improved register, the traveler will appropriate one of the item-dials for each general expense, one for railroad - fare, another for hotel-bills, and the other two for bus, baggage, livery, street-car fares, and incidentals. The register may be carried in the pocket like a watch, and the traveler upon incurring an expense can immediately register the same on the proper item-dial by turning the spindle connected with that dial. If he desires to operate the hands of one of the upper dials, he will turn the spindle toward the left, and through the medium of the clutches and gears connected therewith the long hand will be moved the desired distance and the short hand of that dial will be moved also, but only one twenty-fifth as far as the long hand. For instance, if the traveler desires to register an item of expense of fifty cents on the upper left-hand item-dial of Fig. 1 he will turn the left-hand spindle toward the left and move the long item-hand until it points to the graduation "50" on the dial, and then assuming that both hands start from zero the short or dollar hand will be midway between the zero and the mark indicating one dollar of the inner circle of graduations. If the long hand is moved around to make a complete revolution of the dial and indicate an expense of one dollar, then the total - item hand will be moved to indicate one dollar on the inner circle of graduations. Each time the long or cents hand is moved the total-hand is moved also and completes its revolution of the dollars' graduations of the item-dial when the cents-hand has made twenty-five revolutions of its dial. If it is desired to register an expense on the lower dial on the same side of the register, the traveler simply turns the spindle in the opposite direction from which it is turned to operate the hands of the upper dial. Each time the item-hands

are moved the grand-total hands are moved also, and the totals of the dollars and cents indicated by part or all of the item-dials will be registered on the grand-total dial—for instance, in Fig. 1 the cents-hand of the grand-total dial points to "75," indicating that the sum of all the cents registered on the item-dials amounts to a total of seventy-five cents. The dollars - hand of the grand - total dial points to "50," indicating that the dollars registered on the item-dial amounts to a total of fifty. The traveler is thus able at any time by glancing at the hands of the grand-total dial to ascertain the total amount in dollars and cents of the expenses that have been registered on the item-dials.

While I have described my invention as designed particularly for the use of travelers, it will be understood that it is equally applicable for registering and ascertaining the totals of other items, and it may be used for keeping a record of and ascertaining the totals of receipts as well as disbursements.

I claim as my invention—

1. The combination, with the case, of a dial-plate provided with a series of individual expense-dials having separate graduations for the expense items and for the totals thereof, item and total indicator hands for said dials, a rotating spindle, miter-gears loosely mounted thereon, rotating miter-gears engaged respectively by said loosely - mounted gears, spring-actuated clutches on said spindle normally holding said loosely-mounted gears in engagement with said rotating gears, said clutches being alternately operative when said spindle is turned in opposite directions, suitable gearing provided between said miter rotating gears and said individual-dial hands, whereby said hands will be operated when said spindle is rotated, substantially as described and for the purpose specified.

2. The combination, with a case, of a dial-plate provided with a series of individual expense-dials, item and total indicator hands adapted respectively to register the items of that particular expense for which the dial is appropriated and the totals of such expense, a rotating spindle, miter-gears loosely mounted on said spindle, spring-actuated clutches normally engaging said gears and alternately locking them when said spindle is turned to the left or right, a stud 21 provided between said gears, miter-gears 23 and 24 mounted on said stud and engaging the gears of said spindle respectively, gears 26 and 26^a secured respectively to said gears 23 and 24, operative connections provided between said gears 26 and 26^a and the indicator-hands of two of said individual expense-dials, a grand-total dial, indicator-hands therefor, a gear 28 loosely mounted between said gears 26 and 26^a and locked on its support by the movement of said gears, and operative connections provided between said gear 28 and said grand-total-indicator hands, substantially as described and for the purpose specified.

3. The combination, with a case, of a dial provided with a series of individual expense-dials, item and total indicator hands adapted respectively to register the items of that particular expense for which the dial is appropriated and the totals of such expense, a rotating spindle, miter-gears loosely mounted thereon, spring-actuated clutches for alternately locking said miter-gears when said spindle is turned to the right or to the left, a stud 21, gears 23 and 24 mounted thereon and engaging respectively the miter-gears on said spindle, gears 26 and 26^a secured respectively to said gears 23 and 24, operative connections provided between said gears 26 and 26^a and the item-hands of said individual expense-dials, a reduction-gearing provided between said gears 26 and 26^a and the total-hands of said individual expense-dials, substantially as described and for the purpose specified.
4. The combination, with a case, of a dial-plate provided with four individual expense-dials, two on each side of the center, item and total indicator hands adapted respectively to register the items of that particular expense for which each dial is appropriated and the totals of such expense, rotating spindles for said dials, one spindle being appropriated for the upper and lower dials on each side, miter-gears loosely mounted on said spindle, means for alternately locking said gears according as said spindle is turned to the right or to the left, operative means provided between each of said miter-gears and the indicator-hands respectively of the upper and lower dials, whereby rotation of the spindle in one direction will actuate the hands of one dial and rotation in the other direction will actuate the hands of the other dial, a grand-total dial, indicator-hands therefor adapted to register the totals in dollars and cents of all or any number less than all of said individual dials, and means for actuating said grand-total-indicator hands simultaneously with the movement of said individual expense-hands, substantially as described.
5. The combination, with a case, of a dial-plate provided with a grand-total dial suitably graduated and an upper and lower individual dial, each having two concentric circles of graduations, the inner representing dollars and the outer fractions thereof, suitable indicator-hands for said grand-total and individual dials, a rotating spindle, operative means provided between said spindle and the item-hands of said upper and lower individual dials, whereby said item-hands are alternately operated as said spindle is turned to the left or to the right, a suitable reduction-gearing provided between said operative means and the total-hands of said individual dials, whereby said total-hands will make one revolution of their dials to twenty-five of the

item-hands, a gearing connected with said operative means and with the item-hand of the grand-total dial, and a reduction-gearing provided between said operative means and the total-hand of said grand-total dial, whereby it will make one revolution of its dial to one hundred revolutions of the item-hand, substantially as described and for the purpose specified.

6. The combination, with a suitable case, of a dial-plate provided with a grand-total dial, indicator-hands therefor, a series of individual dials each having graduations for the various items of the particular expense for which that dial is appropriated and also for the totals thereof, suitable item and total indicator hands for said individual dials, rotating spindles for said dials one spindle being appropriated for each pair of dials, operative means connecting each spindle with the hands of the individual dials for which that spindle is appropriated to register the various items of expense on said dials and to indicate simultaneously the totals thereof, suitable means provided between said grand-total dial and said individual dials, whereby the grand-total-indicator hands will be operated simultaneously with the hands of the individual dials to register in dollars and cents the totals of the amounts indicated by the hands of said individual dials, whereby the user at a glance can determine the totals of the expenses for which each individual dial is appropriated and the aggregate totals or expenses indicated by the total and item hands of said dials, substantially as described.

7. The combination, with a case, of a dial-plate provided with four individual expense-dials two on each side of the center, item and total indicator hands adapted, respectively, to register the items of that particular expense for which each dial is appropriated and the totals of such expense, rotating spindles for said dials, one spindle being appropriated for the upper and lower dials on each side, miter-gears loosely mounted on said spindle, means for alternately locking said gears accordingly as said spindle is turned to the right or to the left, operative means provided between each of said miter-gears and the individual hands respectively of the upper and lower dials, whereby rotation of the spindle in one direction will actuate the hands of one dial and rotation in the other direction will actuate the hands of the other dial, substantially as described.

In witness whereof I have hereunto set my hand this 28th day of September, 1901.

HENRY R. RICHARDSON.

In presence of—
RICHARD PAUL,
M. C. NOONAN.
